UNITED STATES PATENT OFFICE.

HENRY H. WAIT, OF CHICAGO, ILLINOIS.

STEAM-TURBINE.

1,274,643.

Specification of Letters Patent.

Patented Aug. 6, 1918.

Application filed September 5, 1916. Serial No. 118,319.

To all whom it may concern:

Be it known that I, HENRY H. WAIT, a citizen of the United States, residing at Chicago, in the county of Cook and State of Illinois, have invented certain new and useful Improvements in Steam-Turbines, of which the following is a specification.

My invention relates more particularly to the mechanism for controlling the speed of the turbine and to provisions for securing the proper lubrication thereof.

In the accompanying drawings I have shown a preferred form of my invention, and in the following specifications described the same in detail. It is to be understood, however, that the specific disclosure is for the purpose of exemplification only, and that the scope of the invention is defined in the following claims in which I have endeavored to distinguish the invention from the prior art so far as known to me without, however, relinquishing or abandoning any portion or feature thereof.

In the accompanying drawings Figure 1 is a central, vertical section partly broken away of a turbine having my invention applied thereto, parts being shown in elevation; Fig. 2 is a vertical section on the line 2--2 of Fig. 6, showing the steam supply pipe and the valves for controlling the supply of steam; Fig. 3 is a horizontal section, on the line 3--3 of Fig. 1, of the turbine bearing upon one side, parts being shown in elevation; Fig. 4 is a vertical transverse section upon the line 4--4 of Fig. 1; Fig. 5, a vertical transverse section upon the line 5--5 of Fig. 1; Fig. 6 a horizontal section through the steam supply pipe upon the line 6--6 of Fig. 2; Fig. 7 a vertical section of a detail, Fig. 8 a vertical transverse section upon the line 8--8 of Fig. 2, and Fig. 9 an enlarged detail of a modification in transverse section. The same reference character is applied to each part wherever it occurs throughout the several views.

The turbine casing is shown at 9, and for the purpose of the present invention it, as well as the turbine wheel 10, may be of any form; though I have shown a turbine of the single stage type. The turbine shaft 11 extends through a stuffing box 12 and is supported in a bearing sleeve 13, carried by a bearing housing 14, bolted at 15 to a bracket 16 cast integral with the casing of the turbine. In the present instance, the bearing housing 14 is formed in two sections sepa-

rated upon the horizontal plane of the axis of the shaft, (Fig. 5) and comprising a bearing chamber proper at 17 which immediately surrounds the shaft and an oil well 18. The bearing sleeve 19 is seated in the bearing chamber and is babbittted at 20 to receive the slightly reduced bearing portion 21 of the turbine shaft. A washer 22 rests against the shoulder 23 and prevents longitudinal motion of the shaft relative to the bearing. The bearing sleeve is formed in two sections 13^a, 18^a, and is cut away upon its opposite sides to form openings 24, the babbittting being grooved in registry with said openings to permit the application of the lubricating ring 25 which dips into the oil well. (See Figs. 1 and 5.) If the shaft is to be removable the lips of the bearing may be made separate therefrom and secured thereto as 75 at 114, (Fig. 9). Relative movement of the bearing sleeve is prevented by the taper pin 26 which is located in the top member 14^a of the bearing housing, and extends into an opening 27 in the bearing sleeve.

On the side thereof remote from the turbine, the bearing housing is formed with an opening 28 somewhat larger in diameter than the opening 29 therein adjacent the turbine, and an annular boss 30 surrounds the first 85 said opening and centers the governor casing 31 which fits about said boss and is secured to the bearing housing by bolts 32 passed through flanges 33 on the casing (Fig. 4). The governor within the casing controls by 90 intermediate means to be presently described, the position of the valve governing the supply of steam to the turbine. It comprises a pair of heavy levers 34 which are rectangular in shape, as shown in Fig. 1, and 95 fulcrumed upon an annular plate 35 which is secured to the shaft of the turbine just within the casing by a pin 36 driven in registering holes in the collar 37 of said plate, and the shaft which collar extends into the 100 opening 28 in the bearing housing. A washer 38 is interposed between the inner end of the collar 37, and a shoulder 39 formed by a slight reduction in the diameter of the turbine shaft and bears upon the end of the 105 babbittted bearing sleeve. As shown in Figs. 1 and 4, the plate 35 is formed with parallel grooves, or recesses 40, formed along diametrically opposite lines on said plate which constitute seats, or fulcra for the pivotal edges 41 of the weight levers 34, and the shorter limbs 42 of the latter are reduced

and extend toward each other and into a transverse opening 43 in the shaft, the plate 35 being cut away as at 44 to permit free movement of the levers. The outer end of 5 the shaft is bored at 45, and the bore communicates with the cross-passage 43 referred to above, and in said bore is slidably mounted a plunger 46, in the inner end of which are secured elastic plates 47, which are 10 formed with knife edges to engage notches 48 in the adjacent ends of the weighted levers. Obviously when the shaft is rotated, carrying with it the plate 35 and the weighted levers, the latter move outward under 15 the centrifugal force, and the inner ends thereof force the plunger 46 in the direction of the arrow in Fig. 1. The outward movement of the plunger, however, is resisted by a spring 49, which is interposed between an 20 adjustable collar 50, screwed upon the end of the shaft, and a sleeve 51 mounted to slide on said shaft, these members being respectively provided with flanges against which the respective ends of the spring bear, 25 and the sliding sleeve is connected to the plunger by a pin or bolt 52 secured at its ends to said sleeve and passing through and snugly fitting an opening in the plunger, the wall of the hollow shaft being formed 30 with elongated openings, or slots 53 to permit of the longitudinal movement of the plunger under the opposed pressures of the spring and weighted levers. The outward movement of the plunger is communicated 35 to a lever 54 which operates the valve as hereinafter described, but in order to avoid undue friction between the lever and the shaft, a bearing is provided which comprises a conical ended pin 55 secured to the shorter 40 arm of said lever extending through a hole 56 in the casing and bearing upon a cup 57 containing a ball bearing 58. The outer end of the plunger is reduced at 59 and surrounded by the bearing and a hardened ring 45 60, which latter transmits the thrust of the plunger to the balls of the bearing. A second hardened ring 61 is interposed between the cup 57 and said balls to avoid undue wear. The outer face of the cup is de- 50 pressed and flattened as at 62 to receive the point of the pin 55 and permit such motion between the parts as is necessary.

The lever 54 is pivoted at 63 to the casing, and its longer arm is engaged by an adjusting spring 64, the other end of which is 55 adjustably connected to a bracket 65 by means of a screw bolt 66. The spring 64 serves to maintain the pin 65 in contact with the cup 57, but the main pressure opposing 60 the outward movement of the plunger under centrifugal action is the spring 49 referred to above.

The steam supply pipe 67 connects with the turbine casing through a valve casing 65 68 and a nozzle stand 69, the flat flange 70

of which is interposed between the valve casing and turbine casing. The valve casing comprises an outer inlet chamber 71 and an inner outlet chamber 72, connected by valve ports 73. A pair of balanced valves 70 74, 75, control these ports and are guided therein by wings 76, and rigidly connected together by a cross-piece including a perforated hub, or enlargement 77. Operating connections from the lever 54 to said balanced valve comprise a rotary shaft 78 journaled in a cover plate 79, an arm 80 on the inner end of said shaft carrying a pin 81 engaging the perforation in the valve stem, and an arm 82 on the outer end of said shaft 75 connected by a link 83 with said lever. The operation of this governor mechanism will now be apparent. When the turbine shaft is revolved the centrifugal action upon the weighted levers 34 forces the plunger outward against the pressure of the spring 49, swinging the lever 54, and through the link 83, arm 82, shaft 78 and arm 80, forcing the balanced valves nearer to their seats. Conversely a reduction of the speed of the turbine is accompanied or followed by a movement of the valves away from their seats, the speed of the turbine thus being maintained at a predetermined number of revolutions per minute. Plugs 84 permit access 80 to the balanced valve.

It is desirable in machines of this character to provide means for preventing the wheel from revolving beyond a predetermined speed in addition to the speed regulator to which reference has been made. In the present construction I provide means for completely stopping the turbine when its speed exceeds a certain limit. For this purpose a butterfly valve 85 is journaled within 105 the steam inlet, and the shaft 86 thereof is extended through the wall of the steam conduit, being packed at 87, and provided with a pedal or foot piece 88. A spring 89 tends to throw the valve to closed position, but it 110 is normally maintained in the open position by a bell-crank latch 90 (Fig. 8) pivoted to a lug 91 upon the valve casing. The bell-crank is connected by means of a link 92 to a trip lever 93, which is pivoted at 94 in 115 the governor casing, and the inner end 95 of which extends into said casing adjacent the periphery of the plate 35 heretofore described. (See Fig. 4). The plate 35 is bored to form a chamber 96 which is closed at its outer end by plug 97, perforated at 98 for the passage of a teat 99 upon a plunger 100. The latter is normally maintained in its innermost position by a spring 101 compressed between the plug and a flange 120 102 upon the plunger. When, however, the speed of rotation of the shaft exceeds a predetermined number of revolutions per minute, the plunger is thrown outward by 125 centrifugal force and the teat engages the 130

- inner end 95 of lever 93. The latter, through the link 92 withdraws the latch 90 from engagement with the foot pedal, and thereupon the spring 89 revolves the butterfly valve to 5 closed position, shutting off the supply of steam to the turbine. The head, or plate 35, is bored at 103 opposite the chamber 101 to equalize the weight distribution of the head 35.
- 10 In order to properly lubricate the ball bearing 58, which is interposed between the revolvable plunger 46 and the lever 54, I provide the bearing cup 57 with a flange-lip or recess 104, (see Fig. 3) which communicates through a passage 105 with the interior of the cup and with the bearing. Oil is supplied to said lip and cup from the bearing of the shaft by a tube 106, the outlet end of which overhangs said lip and the 15 inlet end of which is connected to a passage 107, (Fig. 3) which extends through the wall of the bearing housing and the bearing, and communicates with an inclined channel 108 (Fig. 7) formed in the inner face of the 20 Babbitt metal and extending to a point below the oil ring. The oil passage in the bearing is located upon the side thereof toward which the ring turns as it is revolved by the shaft, and therefore the momentum of the oil and its entrainment by adhesion to the shaft carries it into the inclined channel whence it flows through the 25 passage in the casing and the tube 106 to the bearing cup. In the construction shown, in 30 Fig. 3, I have shown a second channel 107, but only the channel toward which the shaft turns is used, the two channels being provided so that the wheel may be arranged to revolve in either direction with certain 35 changes which it is not necessary here to consider. The bearing cup 57 is formed with a tail-piece or extension 109 which, during the 40 operation of the machine, bears against a bridge 110 to prevent the rotation of cup 45 57, and said tail-piece is longitudinally perforated throughout and communicates with the interior of the cup for the purpose of leading away the oil as it is poured through the bearing. From the tail-piece it drips 50 into the channel 111 and passes through the opening 112 back into the oil chamber of the bearing housing.
- I claim:
1. In a device of the class described, a 55 shaft having a tubular end and a slot communicating with the bore thereof, a head mounted upon the shaft, bell-crank levers 60 fulcrumed on the head and extending through the slot into the bore of the shaft, a plunger mounted in said bore and operatively connected to the levers, a spring for 65 resisting the movement of the plunger under the influence of the levers, a thrust ball bearing at the end of said plunger, a cup surrounding the same, a lever engaging the cup and moved thereby, a motor for operating the shaft, a valve controlling the flow of operating fluid to the motor and connections from the last said lever to the valve for operating the latter. 70
2. In a speed governor of the class described, a rotary shaft having a bored end and a transverse slot connecting with the bore, a head plate mounted upon the shaft adjacent the slot, said head plate having 75 opposite parallel transverse grooves and recesses communicating with said grooves, bell-crank levers fulcrumed in said grooves and extending at their adjacent ends into the recesses in the head plate, and through 80 the slot in the shaft into the bore thereof, a plunger movable in the bore of the shaft and having bearings thereon for the ends of the levers, a spring opposing the movement of the plunger under the influence of 85 the levers, a lever arranged to be acted upon by the plunger when forced outward by the levers, a motor for rotating the shaft, a conduit for supplying motive fluid to the motor, a valve in the conduit and a connection 90 from the last said lever to the valve for operating the latter.
3. In a device of the class described, and in combination with the shaft thereof, said shaft having a hollow end and a transverse 95 slot communicating with the bore thereof, a head plate mounted on the shaft, a pair of oppositely arranged weighted levers fulcrumed on the head plate and having their adjacent ends extending through the slot 100 into the hollow of the shaft, a plunger in the bore of the shaft engaged by the levers, a spring opposing the motion of the plunger under the centrifugal action of the levers, a valve for supplying motive fluid to the 105 motor, connections between the valve and plunger for operating the former, the head plate being formed with a bore at a point on the periphery thereof intermediate the 110 fulcra of the respective levers, a plunger in the bore, a spring normally maintaining the plunger in its innermost position, a trip lever projecting into the path of the plunger when the latter is in its outer position, a pipe for supplying motive fluid to 115 the motor, and a connection between the trip and the valve whereby the operation of the trip causes the valve to close.
4. In a device of the class described and in combination with a rotary shaft having 120 a bored outer end and a transverse slot communicating with the bore, a head plate, levers mounted on the head plate and projecting through the slot into the bore of the shaft, a plunger in the bore of the shaft 125 having a reduced outer end, an annular ball-race mounted on the plunger and surrounding the reduced portion thereof, a ball bearing, the balls of which engage said ball-race, a cup surrounding the bearing, a 130

lever loosely engaging the cup at one end, a conduit for supplying motive fluid to the motor, a valve in said conduit and connections from the valve to the lever.

5. In a device of the class described and in combination with a shaft thereof having a bore in its outer end and a transverse slot communicating with the bore, a head plate on the shaft, levers mounted on the head plate and projecting through the slot into the bore of the shaft, a plunger in the bore engaging the levers, a spring resisting the movement of the plunger under the action of the levers, a thrust roller bearing engaging the end of the shaft, a cup surrounding the bearing having a tail piece for preventing rotation thereof, a lever having a pointed bearing loosely engaging the cup, a valve for controlling the admission of motive fluid to the motor, and connections from the last said lever to the valve for operating the latter.

6. In a device of the class described and in combination with the rotary shaft thereof of having a hollow end and a transverse slot communicating with the bore thereof, a head on the shaft, weighted levers on the head extending through the slot into the bore of the shaft, a plunger mounted in the bore, a spring for resisting the movement of the plunger under the pressure of the levers, means operated by the plunger for controlling the speed of the shaft, a thrust roller bearing intermediate said means and the end of the plunger, a cup inclosing said bearing and a perforated tail piece communicating with the interior of the cup and adapted to prevent the rotation of the latter and to receive lubricant therefrom.

40 7. In a device of the class described and in combination with the rotary shaft thereof, speed governor mechanism mounted on the shaft and including a longitudinally moving plunger, a roller bearing adapted to receive the thrust of the plunger and comprising a cup, means for maintaining the cup against rotation, a lip on the cup communicating with the interior thereof, means for supplying the lip with lubricant, and means bearing upon the cup for controlling the speed of rotation of the shaft.

45 8. In a device of the class described, a rotary shaft, speed governing mechanism on said shaft comprising a plunger moving longitudinally of the shaft, means operated by the plunger for controlling the speed of rotation of the shaft, a thrust bearing intermediate said means and plunger, a bearing surrounding the shaft and in which the latter is journaled, means for supplying oil to the shaft in said bearing, and a conduit leading from said shaft bearing to said thrust bearing and adapted to convey lubricant from the former to the latter.

50 9. In a device of the class described, a ro-

tary shaft, speed governing mechanism on said shaft comprising a plunger moving longitudinally of the shaft, means operated by the plunger for controlling the speed of rotation of the shaft, a thrust bearing intermediate said means and plunger, a bearing surrounding the shaft and in which the latter is journaled, means for supplying oil to said shaft within the bearing, a conduit comprising a passage in the shaft bearing and leading to the thrust bearing for conveying oil from the former to the latter.

55 10. In a device of the class described, a rotary shaft, speed governing mechanism on said shaft comprising a plunger moving longitudinally of the shaft, means operated by the plunger for controlling the speed of rotation of the shaft, a thrust bearing intermediate said means and plunger, a bearing surrounding the shaft and in which the latter is journaled, means for supplying oil to said shaft within the bearing, an inclined oil channel formed in the face of the bearing, and a conduit communicating with said channel and with said thrust bearing to convey oil to the latter.

60 11. In a device of the class described, a rotary shaft, speed governing mechanism on said shaft comprising a plunger moving longitudinally of the shaft, means operated by the plunger for controlling the speed of rotation of the shaft, a thrust bearing intermediate said means and plunger, a bearing surrounding the shaft and in which the latter is journaled, an oil ring adapted to supply the shaft with oil, an oil channel formed in the face of the bearing and arranged to receive the oil supplied by the ring at its intake end, a conduit formed partially in the bearing and communicating with the channel, and with the thrust bearing, and adapted to supply oil to the latter.

65 12. In a device of the class described, a rotary shaft having a speed governor thereon comprising an axially movable plunger, a thrust bearing engaged by said plunger, an annular bearing surrounding the shaft and in which the latter is journaled, an oil ring running on the shaft, an oil well into which said ring dips, a conduit for receiving part of the oil conveyed to said shaft and conveying it to the thrust bearing, and a duct for returning the oil from the thrust bearing to the oil well.

70 13. In a device of the class described and in combination with the rotary shaft thereof, a speed governor mounted on the shaft and comprising a plunger movable axially with relation thereto and revolubly therewith, a thrust plate mounted on the plunger, a second thrust plate receiving the thrust from the first said thrust plate and held against rotary movement, means engaged by the second said thrust plate for controlling the speed of rotation of the shaft, there being a

100

105

110

115

120

125

130

pivotal connection between the last said means and the non-rotary thrust plate.

14. In a device of the class described, a rotary shaft, a centrifugal governor mounted thereon comprising an axially movable plunger, a ball-race on said plunger, a ball bearing engaging said race, a second ball-race engaging the ball bearing, a cup inclosing said ball-races and bearing, a lip on the cup adapted to receive oil and convey it to the ball bearing, and means for preventing the rotation of the cup.

15. In a speed governor of the class described, a rotary shaft, a plunger movable longitudinally of the shaft, a spring opposing the movement of the plunger in one direction, a lever arranged to be acted upon by the plunger when forced outward against the pressure of the spring, a motor for rotating the shaft, a conduit for supplying motive fluid to the motor, a valve in the conduit, a connection from the lever to the valve for operating the latter, a head plate mounted upon the shaft having opposite parallel grooves and radial recesses communicating with said grooves, and bell-crank levers fulcrumed in said grooves, extending at their adjacent ends into the recesses in the head plate, and engaging the plunger to force the same outward against the pressure of the spring.

16. In a device of the class described and in combination with the shaft thereof, a head plate mounted on the shaft, a pair of oppositely-arranged weighted levers fulcrumed on the head plate, a plunger movable longitudinally of the shaft and engaged by the levers, a spring opposing the motion of the plunger under the centrifugal action of the levers, a valve for controlling the supply of motive fluid to the motor, connections between the valve and plunger for operating the former, the head plate being formed with a bore at a point on the periphery thereof intermediate the fulcra of the respective levers, a plunger in the bore, a spring normally maintaining the plunger in its innermost position, a trip lever projecting into the path of the plunger when the latter is in its outer position, and a connection between the trip and the valve whereby the operation of the trip causes the valve to close.

17. In a device of the class described and in combination with a rotary shaft, a head plate, levers mounted on the head plate, a

plunger movable longitudinally of the shaft and engaged by the levers, a spring resisting the movement of the plunger by the levers, a lever operated by the plunger, a rotary bearing intermediate said lever and plunger, a bearing for the rotary shaft, means for supplying the last said bearing with oil, and a conduit for leading oil from the last said bearing to the bearing intermediate the plunger and lever.

18. In a device of the class described, and in combination with the shaft thereof, a plunger movable longitudinally of the shaft, a spring resisting movement of the plunger, centrifugal levers engaging the plunger for moving it against the resistance of the spring, a thrust bearing on the end of the shaft, a cup surrounding the bearing having a tail-piece for preventing rotation thereof, a lever having a pointed bearing loosely engaging the cup, a valve for controlling the admission of motive fluid to the motor, and connections from the last said lever to the valve for operating the latter.

19. In a device of the class described, a rotary shaft, a head plate mounted upon the shaft and having parallel grooves extending across one face thereof, bell crank levers having transverse angular edges seated in the respective grooves thereby forming fulcra, a body reciprocable axially of the shaft, connections from said body to the levers whereby the action of centrifugal force on the levers causes an axial movement of said body, a spring opposing the movement of the body interposed between the same and an abutment on the shaft, means for controlling the admission of motive fluid to drive the shaft, and a connection from said means to said body whereby the movement of the body controls said means.

20. In a speed governor, a rotary shaft, a head plate mounted thereon having parallel grooves upon one face thereof, weighted bell crank levers having angular edges seated in said grooves respectively, and movable about the same as fulcra under the influence of centrifugal force, a body movable axially of the shaft, connections between said body and levers comprising flexible plates secured to the body and bearing upon the adjacent ends of the respective levers, and connections from said body for controlling the speed of movement of the shaft.

HENRY H. WAIT.
